UNITED STATES PATENT OFFICE.

LOUIS SACHSE, OF LOS ANGELES, CALIFORNIA.

GOLD-SAVING APPARATUS.

No. 889,813.

Specification of Letters Patent.

Patented June 2, 1908.

Application filed June 16, 1905. Serial No. 265,490.

To all whom it may concern:

Be it known that I, LOUIS SACHSE, a citizen of the United States, residing at Los Angeles, in the county of Los Angeles and State of California, have invented a new and useful Improvement in Gold-Saving Apparatus, of which the following is a specification.

This invention is an improvement in the gold-saving apparatus patented to me January 19, 1904, and Nov. 15, 1904 by United States Letters-Patent No. 750,227, and No. 774,786, respectively.

The present invention relates to the provision in the amalgamating box of a mercury container forming the bottom of said box, bearings inside said mercury container and a peculiarly constructed roller mounted in said bearings and partially submerged in a body of liquid mercury in said mercury container.

The accompanying drawings illustrate the invention:

Figure 1 is a fragmental cross section, showing the roller in the mercury container. Fig. 2 is an enlarged sectional detail showing the construction of the roller. Fig. 3 is a fragmental elevation at right angles to Fig. 1, showing a roller having concave disks. Fig. 4 is a fragmental view of a roller shown in Fig. 3.

1 is the amalgamating box provided at the bottom with the mercury container 2 which is an integral sheet metal basin fastened to the upper portion of the box.

3 is the liquid mercury or quicksilver in the container 2.

4 is an amalgamating roller comprising copper disks mounted on a shaft 6 and held apart by washers 7 and clamped by nuts 8 screwed on the opposite ends of the shaft.

9 is a gear wheel fixed to the shaft and driven by a worm 10. The shaft 6 is held in boxes 11 which are shown in Fig. 1 fixed to the mercury container 2 and held inside of the same so that said mercury container may be filled with mercury to or above the level of the shaft without danger of leakage.

12 is a gutter to receive the amalgam formed in the quicksilver.

The operation of the roller in the process of amalgamation will be readily understood by those versed in the art.

I claim:

An amalgamating box provided with a detachable mercury container roller bearings entirely inside said container, a shaft mounted in said bearings, disks on said shaft spaced apart by washers and a nut screwed on said shaft and clamping said disks and washers.

In testimony whereof, I have hereunto set my hand at Los Angeles, California this 9th day of June 1905.

LOUIS SACHSE.

In presence of—

JAMES R. TOWNSEND,
JULIA TOWNSEND.
